[57] CLAIM

The ornamental design for a multi-use footwear holder, as shown and described.

DESCRIPTION

FIG. 1 is a perspective view of the multi use footwear holder;

FIG. 2 is a front view of which a rear view is a mirror image thereof;

FIG. 3 is a side view of the multi-use footwear holder of which the opposite side is a mirror image thereof;

FIG. 4 is a top view thereof; and,

FIG. 5 is a bottom view of the ornamental design.

The broken line showing of a strap in FIGS. 1-5 is for illustrative purposes only and forms no part of the claimed design.

FIG. 1.

FIG. 2.

FIG. 3.

FIG. 4.

FIG. 5.
